UNITED STATES PATENT OFFICE.

RAISUKE OGAWA, OF KÖBE, JAPAN.

TELEMOTOR-PISTON.

1,281,996.

Specification of Letters Patent. Patented Oct. 15, 1918.

Application filed May 24, 1917. Serial No. 170,629.

To all whom it may concern:

Be it known that I, RAISUKE OGAWA, a subject of the Emperor of Japan, residing at 83, 7 Chōme, Kamitsutsui Dōri, Kōbe, have invented certain new and useful Improvements in Telemotor-Pistons, of which the following is a specification.

This invention relates to improvements in pistons and more particularly to piston 10 packing for use with telemotor pistons.

The principal object of the invention is to provide a piston, which is fluid-tight in the cylinder, so that fluid or the like cannot leap past the piston.

15 Another object of the invention is to provide a piston of this character with adjustable and elastic means for clamping cup washers to the piston so that said cup washers will yieldingly engage the cylinder.

20 A further feature resides in a construction to uniformly and yieldingly press the cup washers against the cylinder.

With the foregoing object outlined and with other objects in view, the invention consists in the novel features hereinafter described in connection with the accompanying drawing, and more particularly pointed out in the appended claims.

Referring to the drawing:

25 Fig. 1 is a longitudinal sectional view of the piston and a portion of the piston rod and cylinder taken on line I—I of Figs. 3 and 4.

30 Fig. 2 is a half section taken on line II—II of Figs. 3 and 4.

Fig. 3 is an end view looking in the direction of the arrow y, in Figs. 1 and 2.

Fig. 4 is a similar view looking in the direction of the arrow z.

40 Fig. 5 is an edge view of the resilient double ring used for holding the cup washer packings in place.

Figs. 6 and 7 are details of the ring.

45 Figs. 8 and 9 are side views of the ring partly in section.

Fig. 10 is a transverse sectional view taken through the cylinder and piston rod and showing an edge view of one of the yielding clamping rings.

50 The drawing illustrates a telemotor piston used in the steering of ships but it will be understood that my improvements may be used with pistons for other purposes.

In the drawing 1 designates a cylinder in 55 which operates a piston rod 2 provided with a flange 15 having an annular extension 12 provided with an inclined face 16 against

which rests the inclined face of a clamping ring 6. A drum 7 surrounds the rod 2 and is located between the drum and clamping ring 60 is a cup washer packing 3, which has its inner circumference bearing against the rod 2 and its outer circumference bearing against the inner surface of the cylinder, the web connecting the circumferences resting 65 between the clamping ring and drum.

The clamping ring 6 is provided with a series of longitudinally disposed apertures 11 and radially disposed slots 17 extend from these apertures to the periphery of the ring. 70 A circumferential groove 18 is provided in the ring and in this groove is located a double ring consisting of an inner ring 5 and an outer ring 4. The rings 4 and 5 are split as shown, in order to make the same 75 resilient, and the ring 4 is provided with a groove in which the ring 5 rests. As best shown in Figs. 5 to 9, inclusive, the openings between the ends of the rings are arranged out of alignment so that a practically 80 unbroken resilient ring will be provided, which, will bear equally upon all points of the outer circumference of the cup washer packing 3. As shown the opening 4' between the ends of the ring 4 are located at 85 one point while the opening 5' between the ends of the ring 5 are located at a different point, and in order to maintain the rings in this position the ring 4 has a projection 10 which rests in a recess in the ring 5. 90

All of the construction set out in detail, with the exception of the parts 1 and 2 are located on one side of the drum 7, but as seen in the drawing identical parts, in reversed position, are placed on the other side of the 95 drum, with the exception that the fixed flange 15 is substituted by a nut 8, which engages threads on the rod 2. A lock nut 9 holds the nut in place and both nuts are used in adjusting the packings. 100

With this construction, the tightening of the nuts 8 and 9 will cause the inclined faces 16 of the nut 8 and flange 15 to draw the clamping rings 6 toward the rod 2; and also force said clamping rings into engagement with the webs of the washers 3, so that said washers may be tightened after becoming worn. By providing the clamping rings with the slots 17, said rings will bear resiliently on the washers to permit the same 110 to yield slightly without permitting the leakage of fluid.

The double rings 4—5 will bear uniformly and resiliently upon the inner surface of

the outer circumferences of the cup washers and will maintain the same in yielding contact with the inner surface of the cylinder. Also by this construction the wear on the 5 outer circumferences will be automatically taken up.

Passages 13 are provided in the flange 15 and nut 8 to permit the fluid in the cylinder to enter the spaces between the clamping 10 rings and rod 2 and bear upon the edges of the inner circumferences of the washers, to spread the same and provide a tight joint.

In this invention, the webs of the stuffing washers are pressed on the drum, the inner 15 circumferences bear on the rod, and the outer circumferences are yieldingly pressed against the inner surface of the cylinder. Therefore, when, for instance, the washers shrink from long use, the wear will be 20 automatically provided for and perfect watertightness will be kept or maintained. In the known type of pistons, several independent helical springs or one strong spring have or has been employed, as the means 25 for pressing the stuffing washers against the cylinder. But, when several helical springs are used, they cannot be obtained of equal strength, and when one of them is damaged, it is very difficult to get a spring of the same 30 strength to take its place. They are also difficult to combine together in fitting and detaching. On the other hand when using only one spring, it must be of moderate thickness to give it the requisite strength, 35 and this decreases its yieldability or elastic properties.

In contradistinction to these known types, my double spring ring enables me to reduce the thickness of each ring, so that in 40 fitting they do not bend beyond the limit of their yieldability, and are never influenced by the shrinkage or expansion of the stuffing washers. Moreover, when one ring only is used, the pressure along the periphery of 45 the ring is irregular owing to the opening between the ends of the ring. But when the ring is formed of two parts, the gap in each of them can be arranged out of alignment relative to each other, for instance by 90 degrees, so that the pressure due to the elasticity of the ring will be practically uniform.

What I claim and desire to secure by Letters Patent is:

1. The combination with a cylinder, of a 55 piston rod movable therein, and a piston including a cup washer having a web extending transversely of the cylinder, an inner circumference engaging the rod, and an outer circumference engaging the inner surface of the cylinder, and resilient means for holding the outer circumference in engagement with the cylinder.

2. A piston including a rod, a cup washer

arranged upon the rod and consisting of a web extending transversely of the piston and 65 two circumferences concentric with the rod, one of said circumferences engaging the rod and the other adapted to bear upon the inner surface of a cylinder, and resilient means for moving one of the circumferences away 70 from the other.

3. A piston comprising a rod carrying a drum, cup washers surrounding the rod and arranged in reversed positions on opposite sides of the drum, each cup washer including a web which bears upon the drum and two circumferences, one of which engages the rod and the other of which is adapted to bear upon the inner surface of a cylinder, and resilient means for moving one of the 80 circumferences away from the other.

4. A piston including a rod, a cup washer arranged upon the rod and consisting of a web extending transversely of the piston and two circumferences concentric with the rod, 85 one of said circumferences engaging the rod and the other adapted to bear upon the inner surface of a cylinder, and resilient means including a plural section split ring for moving the outer circumference away from the 90 inner circumference.

5. A piston comprising a rod carrying a drum, a cup washer having a web and two circumferences, said web resting on the drum, and said circumferences engaging the 95 rod and the wall of the cylinder in which the piston is placed, a clamping ring for holding the web against the drum, and one circumference against the rod, and a resilient plural section split ring carried by the 100 clamping ring for holding the other circumference against the cylinder.

6. A piston construction comprising a rod carrying a fixed flange having an inclined face, a drum surrounding the rod and spaced 105 away from the flange, a nut threaded to the rod spaced away from the drum and having an inclined face, clamping rings having inclined faces which engage the inclined faces of the nut and flange, cup washers located between the clamping rings and drum and each having a web held against the drum by its respective ring and two circumferences, the inner of which is located between the ring and rod and the outer being 110 adapted to bear on the wall of a cylinder, and plural section resilient rings located between the clamping rings and outer circumferences of the cup washers.

In testimony whereof I have hereunto set 120 my hand in presence of two subscribing witnesses.

RAISUKE OGAWA.
